UNITED STATES PATENT OFFICE.

FRANK CLAUS, OF PHILADELPHIA, PENNSYLVANIA.

POWER-TRANSMITTING DEVICE.

SPECIFICATION forming part of Letters Patent No. 722,491, dated March 10, 1903.

Application filed January 21, 1902. Serial No. 90,637. (No model.)

To all whom it may concern:

Be it known that I, FRANK CLAUS, a subject of the Emperor of Germany, residing at Philadelphia, in the county of Philadelphia and State of Pennsylvania, have invented certain new and useful Improvements in Power-Transmitting Devices, of which the following is a specification.

My invention relates to a mechanical movement; and it consists of a power-transmitting device whereby a reciprocating motion may be converted into a rotary motion.

My improved device may be applied either in conjunction with manually-operated devices or power and may be used in connection with sewing-machines, lathes, woodworking machinery, hoisting-engines, and printing or stamping presses.

My invention will be more fully understood by reference to the accompanying drawings, in which—

Figure 1 illustrates a plan view of a mechanical movement embodying my invention. Fig. 2 represents a side elevation of same. Fig. 3 illustrates a vertical section taken on the line 33 of Fig. 1. Fig. 4 shows a detached sectional plan view of one of the clutches, enlarged, the outer covering of the parts being broken away on a line 44 of Fig. 3. Figs. 5 and 6 are diagrammatic views of the clutches in position to transmit, respectively, a forward and backward motion to the rotating parts of the machine; and Fig. 7 is a detached perspective view of the clutch-levers.

Referring to the reference-letters of the drawings, A represents a reciprocating bar, which may be connected to any reciprocating prime mover—such, for instance, as the piston of a steam-engine or other reciprocating motive power. This bar is provided above and below with racks A' and A'', which engage pinions B' and B'', loosely supported upon shafts B¹¹ and B¹². Each of these pinions is provided with a hub b, through which passes a slideable bar C, which is united to a grooved collar D, loosely supported upon the shaft supporting the pinions. The collar D is operated by a lever E, having a bifurcated end inclosing the collar, and pins e e, adapted to the groove thereof. The lever E is fulcrumed at E and is connected to a notched operating-plate E², provided with an operating fin-

ger-piece E³. The plate E² is provided with three notches e', e'', and e³, which are caused to engage the edge of a plate F to hold the lever E in position by means of a spiral spring S. The lower pinion B'', which is loosely mounted on a shaft B¹², has a similarly-arranged collar D, and the connecting parts are identical with those just described and are indicated by similar letters of reference. In the rear of the pinions B' and B'' are cup-shaped disks G G, each being secured to its respective shaft by means of set-screws g g. The shafts B¹¹ and B¹² are provided, respectively, with gear-wheels H and H', which engage a broad pinion I, mounted upon a shaft J, provided with a fly-wheel K. Arranged between the pinion B' and the disk G and between the pinion B'' and lower disk G is the clutch mechanism by which the pinions may be connected with the disks to operate them in either direction, or, if desired, by moving the levers E to the proper position one or both of the clutches may be thrown out of action. As both of the clutches are identical in construction, a description of one will suffice for the other, and similar letters of reference will be employed to designate similar parts in both cases. The hub b of each of the pinions is recessed at b' to receive the sliding bar C, which is slightly concave on its upper surface, as shown at c. The sliding bar is provided near its end with an inclined slot C' to receive a pin C'', which is projected from a lever C¹², hinged to toggle-levers C¹³ and C¹⁴.

Closely engaging the inner wall of the cupped disk G is a split ring G', which has rounded ends adapted to concave surface-forming sockets in the toggle-levers C¹³ and C¹⁴. The toggle-levers are spread out and the ends of the split ring are caused to embrace the inner wall of the cupped disk by means of an elliptic spring S', which is held by a support c¹² on the hub b and bears against a cross-piece c¹³, arranged upon the pin c¹⁴, which connects the levers C¹², C¹³, and C¹⁴.

When the machine is in operation, each of the levers E is operated, so that the notch e² is in engagement with the plate F, as shown in Fig. 1. Then the clutches are thrown out of action. If, however, the lever E be moved

so that the notch e^3 is in engagement with the plate F, then the levers C¹², C¹³, and C¹⁴ will assume the position shown in the diagram Fig. 5, and a movement of the bar A will cause the rotatable parts to move in the direction indicated by the full arrows shown in Fig. 1. If the lever E be shifted so that the notch e' is in engagement with the plate F, the levers C¹², C¹³, and C¹⁴ will assume the position shown in the diagram Fig. 6, and the rotatable parts of the device by a movement of the bar A will turn in the direction indicated by the dotted arrows in Fig. 1.

Having described my invention, what I claim, and desire to secure by Letters Patent, is—

1. A power-transmitting device comprising a bar adapted to be reciprocated, pinions engaging the bar and loosely journaled upon shafts, gear-wheels fixedly secured to the shafts, a pinion mounted upon a shaft and in engagement with said gear-wheels and clutch mechanism located between the loose pinions and their supporting-shafts, substantially as specified.
2. A power-transmitting device comprising a bar adapted to be reciprocated, pinions loosely journaled upon shafts and engaging the bar, disks fixedly secured to the shafts carrying the pinions, clutches arranged between the pinions and disks, a pinion mounted upon a driven shaft, the gears fixedly secured to the first-mentioned shafts engaging said pinion, substantially as specified.
3. A power-transmitting device comprising a bar adapted to reciprocate provided with upper and lower racks, pinions engaging said racks and loosely journaled upon shafts, disks fixedly secured to said shafts, reversible clutch mechanism between the pinions and disks and levers for operating said clutches, substantially as specified.
4. A power-transmitting device comprising a bar adapted to reciprocate having teeth arranged upon the upper and lower sides thereof, pinions engaging the same, shafts supporting the pinions, disks fixedly secured to the shafts, reversible clutches between the pinions and disks, levers for operating said

clutches, gear-wheels mounted upon each of 50 said shafts, and a shaft provided with a pinion of sufficient width to engage both of the gear-wheels, substantially as specified.

5. A power-transmitting device comprising a bar adapted to reciprocate having teeth arranged upon opposite sides thereof, pinions engaging the same, shafts loosely supporting the pinions, disks fixedly secured to the shafts, reversible clutches arranged between the pinions and disks, levers for operating the 60 clutches, a driven shaft, and a train of gears arranged between the clutches and driven shaft, substantially as specified.

6. A power-transmitting device comprising a bar adapted to reciprocate provided with 65 racks, pinions loosely supported upon shafts engaging the rack, the same being provided with projecting hubs, cup-shaped disks enclosing the hubs and fixedly secured to said shafts, split rings arranged within said disks, 70 toggle-levers engaging the ends of the rings, sliding bars for operating the toggles, means for operating the sliding bars, gear-wheels fixedly secured to the first-mentioned shafts and a pinion mounted upon a shaft and in 75 engagement with each of said gear-wheels, substantially as specified.

7. A power-transmitting device comprising a bar adapted to reciprocate provided above and below with a toothed rack, means for operating said bar, pinions arranged above and below the bar engaging the teeth of the rack, 80 shafts loosely supporting the pinions, disks fixedly secured to the shafts, reversible clutch mechanism between the pinions and disks, 85 sliding bars carried by said pinions for operating the clutch mechanism, levers for operating said bars, notched plates to secure said levers in position, gear-wheels fixedly secured to said shafts and a pinion mounted upon a 90 shaft and engaging both of said gear-wheels, substantially as specified.

In testimony whereof I affix my signature in presence of two witnesses.

FRANK CLAUS.
